UNITED STATES PATENT OFFICE.

JOSEPH A. COSTELLO, OF CLEVELAND, OHIO.

ART OF MAKING HOT-PRESSED NUT-BLANKS.

1,287,644.

Specification of Letters Patent. Patented Dec. 17, 1918.

Application filed February 16, 1918. Serial No. 217,698.

To all whom it may concern:

Be it known that I, JOSEPH A. COSTELLO, a citizen of the United States, residing at Cleveland, in the county of Cuyahoga and State of Ohio, have invented a new and useful Improvement in the Art of Making Hot-Pressed Nut-Blanks, of which the following is a specification.

This invention relates to an improvement in the art of making hot-pressed or forged hexagonal nut-blanks which have substantially the same diameter between any two diametrically opposite corners thereof, and pertains more especially to a process in carrying out which it will hereinafter be observed that the hot metal piece employed in producing the desired nut-blank is hexagonal in cross-section and smaller than said nut-blank in cross-section, that said piece is inclosed circumferentially of its range of movement while being operated on and pressure is exerted against only the central portion of one end face of said piece while supporting the other end face of said piece so as to form a bore extending endwise of said piece from the first-mentioned face in the direction of the second-mentioned face and so as to displace metal from said piece in the opposite direction at the outer portion of the first-mentioned face, that upon the formation of said bore pressure against the aforesaid central portion of the first-mentioned face is removed and metal which has been displaced in the second-mentioned direction at the outer portion of the first-mentioned face is forced in the first-mentioned direction while supporting the surrounding wall of said bore and while supporting the second-mentioned face, that thereupon pressure is removed from the outer portion of the first-mentioned face and support is removed from said wall, and that finally pressure is exerted against only the central portion of said second-mentioned face and in line endwise with said bore while holding the hot piece at the outer portion of the first-mentioned face against movement in the second-mentioned direction so as to separate said metal from the remainder of the hot piece and thereby complete the formation of a hole extending endwise of and through the resulting blank while the second-mentioned face is unsupported circumferentially of said hole and while the first-mentioned face is supported circumferentially of said hole.

The primary object of this invention is to simplify and facilitate the manufacture of forged hexagonal nut-blanks which are ready to be screw-threaded internally as required to form finished nuts and in the best possible condition for the production of perfect hexagonal nuts.

With this object in view, and to attain any other object hereinafter appearing, this invention consists in the steps or process hereinafter described in this specification, and pointed out in the claims.

Apparatus suitable for use in carrying out my improved process is illustrated in the accompanying drawings in which Figures 1, 2 and 3 are vertical sections of said apparatus. Figs. 4 and 5 are transverse sections taken along the lines 4—4 and 5—5, respectively, Fig. 2, looking in the direction indicated by the arrows. Fig. 6 is a transverse section taken along the line 6—6, Fig. 3, looking in the direction indicated by the arrow. Figs. 7, 8, 9 and 10 are vertical sections of said apparatus. Fig. 11 is a transverse section taken along the line 11—11, Fig. 8. Fig. 12 is a transverse section taken along the line 12—12, Fig. 10.

Referring to said drawings, A indicates a stationary die provided interiorly with a bore *a* which is hexagonal in cross-section and extends endwise of and through the die and is adapted to receive a hexagonal hot metal piece B which is to be pressed or forged into an hexagonal nut-blank having the external shape and dimensions of a finished hexagonal nut. The bore *a* therefore forms a chamber which is hexagonal in cross-section, as shown in Figs. 4, 5, 6, 11 and 12, to conform to the external contour of said hexagonal nut in cross-section and has substantially the same diameter between any two diametrically opposite corners thereof. The die A is rendered stationary in any approved manner.

And endwise movable plunger, which comprises a tubular member C and a solid member D arranged within and longitudinally of said tubular and outer member, is employed in introducing the hot metal piece B into the die A, and said piece is hexagonal and smaller in cross-section than the finished nut-blank and enough smaller than the bore *a* in cross-section to render it capable of easily entering said bore, and preferably the hot piece is smaller in diameter between two diametrically opposite corners *x* there-

of than between any other two diametrically opposite corners of said piece, as shown in Fig. 5.

In Fig. 1 of the drawings the members C and D of the hereinbefore mentioned plunger are shown flush or in line transversely at their forward end faces, and said members are movable endwise together or independently of each other. The hot piece B is 10 of course held in any approved manner between the die A and said plunger preparatory to the forward movement of the plunger, whereupon both plunger-members C and D are advanced so as to introduce the 15 hot piece into the die, as shown in Fig. 1. The outer plunger-member C of course conforms in cross-section, as shown in Fig. 11, to the internal contour of the die in cross-section, and the inner plunger-member D is 20 circular in cross-section, as shown in Figs. 5, 6 and 11, and preferably somewhat rounded at its forward end face, as shown in Figs. 1, 2, 3, 7, 8, 9 and 10. The inner plunger-member D substantially corresponds in diameter to the 25 diameter of the bore to be formed in the hot piece B by said inner plunger-member as will hereinafter appear. It will be observed that the hot piece B is fed into and endwise of the die A from one end of the bore *a* in 30 the die, and an endwise movable blank-ejector E extends in any position thereof into the die from the opposite end of said bore and is spaced in its extreme rearward position, shown in Figs. 1, 2, 3, 7, 8 and 9, 35 far enough from the forward end of the die to permit the hot piece, which is to be operated on within the die, to be inserted into the die by the plunger and to permit the plunger-members C and D to move within 40 the die during the movement of and operation on said piece within the die. The ejector E of course conforms in cross-section externally to the internal contour of the die in cross-section, as shown in Fig. 4, and a 45 punch G is arranged centrally and longitudinally of the ejector. The ejector E is therefore tubular, and said ejector and the punch G are shiftable endwise independently of each other. In their extreme rearward position, shown in Figs. 1, 2, 3, 7 and 50 8, said punch and said ejector are flush at their forward end faces. It will be observed that the outer plunger-member D and the ejector E correspond in external and internal diameter and are arranged in line 55 endwise, and that the inner plunger-member D and the punch G correspond in diameter and are arranged in line endwise.

In carrying out my improved process the 60 ejector E and the punch G are held in their extreme rearward position, shown in Figs. 1, 2, 3, 7 and 8, while the hot piece B is being moved and operated on with the die A. Fig. 2 shows the inner plunger-member D as having 65 been actuated forwardly independently

of the outer plunger-member C and as having moved the hot piece B within and endwise of the die and into contact with the ejector which is provided at its face with projections *e* arranged and contoured as required to render it capable of properly crowning the blank to be made. That is, the hot piece B is moved by the inner plunger-member D in the direction of and into contact with the projections *e* of the ejector, as 70 shown in Fig. 2. The forward movement of the outer plunger-member C is arrested at such a predetermined moment that when the inner plunger-member D has fed the hot piece into contact with the ejector the outer 75 plunger-member is spaced from said piece a distance measuring more than one-half of the distance between the end faces of said piece, as shown in Fig. 2, so that both plunger-members can, upon the feeding of the 80 hot piece into contact with the projections *e* of the ejector by the inner plunger-member, be advanced together, and so that, while both plunger-members are thus being advanced together, the inner plunger-member 85 moves into the hot piece to a point about half way between the end faces of said piece, as shown in Fig. 3. It will be observed therefore that, as shown in Fig. 3, pressure 90 is exerted by the inner plunger-member D 95 during the forward movement of said inner plunger-member against the central portion 100 of the adjacent end face of the hot piece while the ejector and the punch remain stationary and thereby support and consequently exert pressure against substantially the whole of the other end face of said piece so as to effect the formation, by said inner plunger-member, of a bore *b* which extends 105 from the first-mentioned face into and endwise of the hot piece a suitable distance in the direction of the second-mentioned face but not through said piece. It will be observed therefore that, during the forward movement of the inner plunger-member into 110 the hot metal piece pressure is exerted against only the central portion of one end face of said piece while supporting the other end face of said piece, and that during the 115 formation of the bore *b* metal is displaced from said piece against the surrounding walls of the bore *a* in the die, and there is a displacement of metal, as at 13, Fig. 3, from the outer portion of the hot piece toward 120 and in front of the outer plunger-member, 125 The outer plunger-member, during the formation of the bore *b*, is held spaced far enough from the hot piece to permit of the last-mentioned displacement of metal without liability of the displaced metal coming 130 into contact with said plunger-member. Upon the formation of said bore the inner plunger-member is withdrawn about or somewhat more than a sixteenth of an inch from the end wall of the bore, as shown in 130

Fig. 7, to remove the pressure or support from said wall but not far enough to remove support from the surrounding wall of said bore. Thereupon the outer plunger-member, while the inner plunger-member and the ejector and the punch are held stationary in the position shown in Fig. 7 and while the inner plunger-member is affording support to the surrounding wall of said bore, is advanced independently of the inner plunger-member from its position shown in Fig. 3 into the position shown in Fig. 7,—that is, such a distance as to cause the displaced metal 13 to be forced in the direction of the 10 ejector and thereby insure the formation of a nut-blank which is perfect in external configuration and in fine condition throughout. It will be observed therefore that while the hot metal piece has its displaced metal 13 at 15 one end face of said piece forced by the outer plunger-member in the direction of the ejector the surrounding wall of the bore *b* is supported by the inner plunger-member and the whole of the other end face of the hot 20 piece is supported by the ejector and the punch, and that obviously said punch and the ejector exert pressure against the whole of the last-mentioned face during the pressing operation of the outer plunger-member, 25 The removal of pressure from the inner end wall of the bore *b* while the surrounding wall of the bore is still supported during the exerting of pressure against the whole of the last-mentioned face and against the 30 outer portion of the other end face of the hot piece permits of the displacement of metal from said wall in the direction of the outer end of the bore should there be an excess of metal in the hot piece, so that 35 40 undue tightening of said piece in the die, and shrinkage and consequent unduly tightening of said piece onto the inner plunger-member during the exertion of pressure against the ends of said piece by the outer 45 plunger-member and by the ejector and the punch, as shown in Fig. 7, are prevented.

Upon pressing the hot piece by and between the outer plunger-member and the ejector, as shown in Fig. 7, the said plunger-member is withdrawn from the hot piece about or somewhat more than a sixteenth of an inch, as shown in Fig. 8, and the inner plunger-member is withdrawn from said piece into the outer plunger-member a suitable distance beyond the face of the outer plunger-member, as shown in Figs. 8, 9 and 10, so that pressure has been removed from the end faces of the hot piece. Then the punch *G*, while the ejector and the outer plunger-member are held stationary, is advanced and thereby feeds the hot piece away from the ejector and into contact with the outer plunger-member, as shown in Fig. 9, whereupon, while the ejector is held stationary and spaced from the hot piece and while

said piece is held by the outer plunger-member against movement farther from the ejector, the punch is advanced far enough, as shown in Fig. 10, to punch the metal 14 between the inner end of the bore *b* and the 70 punch in the direction of the inner plunger-member and thereby separate said metal from the remainder of the hot piece and force said metal through said bore and into the outer plunger-member in front of the 75 inner plunger-member, as shown in Fig. 10, so as to complete the formation of a hole extending endwise of and through the resulting blank, while the crowned end face of said blank is unsupported circumferentially 80 of said hole and while the other end face of the blank is supported circumferentially of said hole. The removal of pressure from the crowned end face of the hot piece by spacing said piece from the ejector preparatory to 85 punching the metal 14 from said piece permits of the displacement of metal from said piece at the outer portion of said face in the direction of the ejector,—that is, in a direction opposite to the direction in which the 90 metal 14 is punched from the hot piece,—should there be an excess of metal in the said piece, so that undue tightening of said piece in the die, and shrinkage and consequent unduly tightening of said piece onto 95 the punch during the punching of said metal 14 from said piece, are prevented.

After the metal 14 has been punched from the hot piece in the manner hereinbefore described the outer plunger-member is withdrawn far enough from the die to permit the ejector to advance and discharge the resulting tubular nut-blank from the die, whereupon the ejector is returned into its most rearward position and the inner 100 plunger-member is advanced independently of the outer plunger-member the distance required to effect the discharge from the outer plunger-member of the metal 14 previously delivered into the outer plunger-member, and thereupon the two plunger-members are positioned as required preparatory to the feeding of another hot metal piece into the die.

I would here remark that not unimportant to a successful practice of my invention is to have the hot metal piece to be operated on not only smaller diametrically than the bore *a* in the die to render said piece capable of readily entering said bore 120 but smaller diametrically between two diametrically opposite angles or corners of said piece than at the remaining corners of said piece, as shown in Fig. 5, so as to prevent an unduly tight fit between said piece and the walls of said bore during the operations 125 illustrated in Figs. 3 and 7.

By the process hereinbefore described it will be observed that the entering of the hot metal piece by the inner plunger-member 130

and by the punch simultaneously is avoided, so as to prevent displacement of too much metal at one time and to help in insuring that the hot piece shall not be shrunk or 5 unduly tightened on the punch and inner plunger-member.

What I claim is—

1. In the art of making forged or hot-pressed nut-blanks, an improvement consisting in inclosing the hot metal piece circumferentially of its range of movement while being operated on and exerting pressure against only the central portion of one end face of said piece while supporting the 10 other end face of said piece and thereby forming a bore which extends endwise of said piece from the first-mentioned face in the direction of the second-mentioned face, then removing the pressure from the end 15 wall of said bore and exerting pressure against the outer portion of the first-mentioned face while supporting the surrounding wall of said bore and while supporting the second-mentioned face, and finally 20 punching the metal between the inner end of said bore and the second-mentioned face and thereby completing the formation of a hole extending endwise of and through the resulting blank while the second-mentioned 25 face is unsupported circumferentially of said hole and while the first-mentioned face is supported circumferentially of said hole.
2. In the art of making nut-blanks, an improvement consisting in inclosing the hot 30 metal piece circumferentially of its range of movement while being operated on and exerting pressure against only the central portion of one end face of said piece while supporting the other end face of said piece 35 and thereby forming a bore which extends endwise of said piece from the first-mentioned face and permitting said piece to have metal displaced therefrom at the outer portion of said first-mentioned face, then 40 removing the pressure from the end wall of said bore and exerting pressure against said outer portion of said first-mentioned face while supporting the surrounding wall of said bore and while supporting the second-mentioned face, then removing the support 45 from the last-mentioned wall and exerting pressure against only the central portion of the second-mentioned face and in line endwise with the aforesaid bore while supporting 50 the aforesaid outer portion of the first-mentioned face and thereby separating the metal between the inner end of said bore and the second-mentioned face from the remainder of the hot piece and completing 55 the formation of a hole extending endwise of and through the resulting blank.
3. In the art of making nut-blanks, an improvement consisting in inclosing the hot 60 metal piece circumferentially of its range of movement while being operated on and exerting pressure against only the central portion of one end face of said piece while supporting the other end face of said piece and thereby forming a bore extending endwise of said piece from the first-mentioned face, then exerting pres- 65

erting pressure against only the central portion of one end face of said piece while supporting the other end face of said piece and thereby forming a bore extending endwise of said piece from the first-mentioned face, 70 then exerting pressure against the outer portion of said first-mentioned face while supporting the surrounding wall of said bore and while supporting the second-mentioned face, and then removing the pressure or support from the outer portion of said second-mentioned face and from the surrounding wall of said bore and exerting pressure against only the central portion of the second-mentioned face in line endwise with 75 said bore while supporting the hot piece at the outer portion of the first-mentioned face and thereby separating the metal between the inner end of said bore and the second-mentioned face from the remainder of said 80 piece.

4. In the art of making nut-blanks, an improvement consisting in inclosing the hot metal piece circumferentially of its range of movement while being operated on and exerting pressure against only the central portion of one end face of said piece while supporting the other end face of said piece and thereby forming a bore extending from the first-mentioned face in the direction of 90 the second-mentioned face, then removing the pressure against the end wall of said bore and exerting pressure against the outer portion of the first-mentioned face while supporting the surrounding wall of said bore and while supporting the second-mentioned face, then removing the pressure from the outer portion of said second-mentioned face, and then punching the metal between the inner end of said bore and the 95 second-mentioned face and thereby separating said metal from the remainder of the hot piece and completing the formation of a hole extending endwise of and through the resulting blank while the second-mentioned 100 face is unsupported circumferentially of said hole and while the first-mentioned face is supported circumferentially of said hole.

5. In the art of making a hexagonal nut-blank which has substantially the same 110 diameter between any two diametrically opposite corners thereof, an improvement consisting in providing a hexagonal hot metal piece which is smaller in diameter between two diametrically opposite corners thereof 115 than between any other diametrically opposite corners of the piece and inclosing said piece in a chamber which substantially corresponds in cross-section to the aforesaid nut-blank, then exerting pressure against 120 only the central portion of one end face of the hot piece while supporting the other end face of said piece and thereby forming a bore extending endwise of said piece from the first-mentioned face, then exerting pres- 125

sure against the outer portion of said first-mentioned face while supporting the second-mentioned face, and finally punching the metal between the inner end of said bore 5 and the second-mentioned face and thereby separating said metal from the remainder of the hot piece.

6. In the art of making a hexagonal nut-blank which has substantially the same diameter between any two diametrically opposite corners thereof, an improvement consisting in providing a hexagonal hot metal piece which is smaller in diameter between two diametrically opposite corners thereof 10 than between any other diametrically opposite corners of the piece and inclosing said piece in a chamber substantially corresponding in cross-section to the aforesaid blank, then exerting pressure against only the central portion of one end face of the hot piece 15 while supporting the other end face of said piece and thereby forming a bore extending endwise of said piece from the first-men-

tioned face, then removing the pressure against the end wall of said bore and exerting pressure against the outer portion of the first-mentioned face while supporting the surrounding wall of said bore and while supporting the second-mentioned face, and then removing the pressure or support from 25 the outer portion of said second-mentioned face and exerting pressure against only the central portion of the second-mentioned face in line endwise with said bore while supporting the outer portion of the first-mentioned face and thereby separating the metal between the inner end of said bore and the second-mentioned face from the remainder of the hot piece.

In testimony whereof, I sign the foregoing 30 specification, in the presence of two witnesses.

JOSEPH A. COSTELLO.
